UNITED STATES PATENT OFFICE.

ROLAND D. GOULD, OF HOOD RIVER, OREGON.

DESIGN FOR A LAMP-SHADE.

No. 40,177.

Specification for Design.

Patented July 27, 1909.

Application filed May 17, 1909. Serial No. 496,672. Term of patent 14 years.

To all whom it may concern:

Be it known that I, ROLAND D. GOULD, a citizen of the United States, residing at Hood River, in the county of Wasco and State of Oregon, have invented a new, original, and ornamental Design for Lamp-Shades, of which the following is a specification, reference being had to the accompanying drawing, forming part thereof.

The figure is a side elevation of a lamp shade showing my new design.

The lamp shade which is shown in the drawing comprises a cylindrical body A which is ornamented with a series of spaced bands extending from the lower end of the cylindrical body spirally toward the upper

end of the body, the bands being alternately colored or frosted. The upper and lower ends of the cylindrical body A are each formed with a concave annular bead B. Above the uppermost bead is a flat, colored band from which extends a concavely curved neck, C, contracted at its upper end and supporting a frosted globular finial, D.

I claim:

The ornamental design for a lamp shade as shown.

ROLAND D. GOULD. [L. S.]
